S. H. GIBSON

VALVE FOR USE WITH BARRELS

Filed April 11, 1921

Fig. 1.

Fig. 2.

UNITED STATES PATENT OFFICE.

SAMUEL H. GIBSON, OF CLEVELAND, OHIO, ASSIGNOR TO THE FANNER MANUFACTURING COMPANY, OF CLEVELAND, OHIO, A CORPORATION OF OHIO.

VALVE FOR USE WITH BARRELS.

Application filed April 11, 1921. Serial No. 460,263.

To all whom it may concern:

Be it known that I, SAMUEL H. GIBSON, a citizen of the United States, residing at Cleveland, in the county of Cuyahoga and State of Ohio, have invented a certain new and useful Improvement in Valves for Use with Barrels, of which the following is a full, clear, and exact description.

The present invention relates to a faucet or valve construction which is particularly adapted to be used in connection with barrels, more particularly metal barrels, the construction being such that the faucet may be assembled with respect to the barrel so as to be on the inside thereof during shipment, but readily removed and mounted to extend on the outside thereof for the dispensing of the liquid material which is contained in the barrel.

The object of the invention is to provide a faucet of the character described which may be made at low cost of manufacture and will accommodate itself to the standardized fittings with which such barrels are customarily provided.

Reference should be had to the accompanying drawings forming a part of this specification in which Fig. 1 is an elevation with portions in section showing the faucet applied to a barrel and extending on the outside thereof; Fig. 2 is a sectional elevation showing the position of the faucet upon the inside of the barrel; Fig. 3 is an elevation with portions in section showing the faucet extending from the outside of the barrel; Fig. 4 is an elevation with portions in section of a modified construction.

Steel barrels at the present time commonly assume the shape and construction which is indicated in Fig. 1, wherein there is provided a head 1 with an opening therein such as indicated at 2 of sufficient size to permit the filling of the barrel conveniently and expeditiously. This opening is closed by a metal plug or bung which is indicated at 3. These barrel heads are also provided with a second opening such as indicated at 4 which is adapted to receive the threaded end of a faucet by which the contents of the barrel may be dispensed. It is customary to close this opening by means of a plug during shipment and when it is desired to dispense the contents of the barrel, to remove the plug and insert in the threaded opening a suitable faucet.

The present invention is designed to provide a faucet of such size that it will go through the relatively small threaded opening 4, the body of the faucet extending within the barrel and suitably held, during shipment, and when the barrel has reached its destination and it is desired to dispense the contents, the faucet may be removed from the threaded opening, reversed, and again threaded into the opening, the body of the faucet extending outwardly into convenient position to accommodate receptacles to which the contents of the barrel are to be delivered.

In the present instance the body of the valve is indicated at 5. Adjacent one end the body of the valve is provided with an extension 6 of reduced diameter and the same is threaded upon its outer surface as indicated at 7. Upon this reduced portion 6 there is mounted an internally threaded bushing 8 which is also provided with threads upon its outer surface by which it may be mounted in the threaded opening 4 of the barrel. This bushing has a head 8a which is adapted to engage against the outer surface of the barrel when the bushing 8 is in its final position. There is also provided a nut 9 which is threaded upon the reduced portion 6 of the faucet body, the nut 9 acting as a lock nut to prevent relative rotation of the bushing with respect to the body of the faucet.

The valve body is provided with a central passageway 5a and at the end thereof which is opposite to the reduced portion 6, the valve body is provided with a recess of enlarged diameter which is partially threaded as indicated at 5b. The enlarged portion at the end of the faucet body provides a shoulder 5c against which a plug 10 is adapted to engage. The plug 10 may conveniently be provided with a washer 10a as is usual in valve construction. A portion of the plug is threaded as indicated at 10b and cooperates with a threaded portion 5b as before described. The plug is also provided with an extension 10c by which extension the plug 10 may be rotated so as to seat or unseat the plug. While any convenient means may be employed for rotating the plug 10 it is preferred to construct the projection 10c with one or more flat sides which may conveniently be engaged by a wrench and such a wrench is shown as 110.

comprising a flat member 11 provided with a hole 12^a which is complimentary to the shape of the extension 10^c so that when mounted thereon the member 11 may be utilized to move the plug 10.

The body 5 is provided with an opening 5^a which is an outlet opening, this outlet opening lying beyond the valve seat and when the plug 10 is moved from the valve seat the interior passageway 5^a is in communication with the opening 5^a.

During shipment of the barrel the operating handle 11 may be placed within the body 5 as forming a convenient storage place for the same. In order to prevent the handle 11 from dropping out a plug 12 is provided which is threaded into the end of the opening in the faucet body 5.

In Fig. 4 an alternative construction is shown wherein a single cap member is made to serve not only as a closure for the end of the opening in the valve body 5, but also to function as a locking nut in place of the nut 9. The cap member referred to is shown in Fig. 4 and indicated at 13 and is threaded so that it may be mounted upon the threads 7 at the end of the valve body 5. This cap member when turned to its innermost position engages with the head 8^a of the bushing 8 serving as a locking member and also as a closure member for the open end of the valve body.

In assembling the valve body with respect to a barrel the valve body and bushing 8 are first assembled, the locking nut 9 or locking cap 13 as the case may be, properly mounted, and then the valve body is inserted through the opening 4 of the barrel, the bushing 8 and the parts assembled therewith being turned until the head 8^a of the bushing engages firmly with the head of the barrel.

In removing the faucet so as to dispense the contents of the barrel, the bushing 8 with the parts attached thereto is removed, the lock nut 9 or the cap 13 removed, and where the plug 12 is used, it too is removed. The valve body is then disassociated from the bushing 8 and the bushing is again threaded up on the extensions 6, but in its reversed position so that the valve body proper may be said to extend outwardly

from the head of the bushing and occupying the position which is indicated in Fig. 3 of the drawing. In this position the plug 10 may be operated as required to dispense the contents of the barrel.

The whole faucet structure and the parts associated therewith form a self-contained unit which is adaptable to be mounted within the barrel for shipment and to be mounted on the exterior of the barrel for dispensing purposes.

Having described my invention, I claim—

1. A barrel having an opening therein, a bushing removably mounted in said opening, said bushing being provided with internal screw threads, a hollow valve body, a valve cooperating with said hollow valve body, said valve body having a threaded end portion adapted to be screwed into the bushing, said threaded portion of the body being of a length to extend through the bushing and project beyond the end thereof when fully screwed therein and said valve body being insertible into the bushing from either end of the bushing, and a lock nut adapted to be screwed on the threaded end of the valve body which projects beyond the end of the bushing, said lock nut being engageable with the end of the bushing.

2. A barrel having an opening therein, a bushing removably mounted in said opening, said bushing being provided with a central threaded opening, a hollow valve body, a valve cooperating with said hollow valve body, said valve body having an end portion threaded to cooperate with the opening in the bushing, said threaded portion of the body being of a length to project through and beyond the end of the bushing when fully screwed therein and said valve body being insertible in the bushing from either end of the bushing, and a cap member for closing the open end of the valve body, said cap member being adapted to be threaded on the end of the valve body which projects beyond the end of the bushing and engageable with the end of the bushing whereby it serves as a lock nut.

In testimony whereof, I hereunto affix my signature.

SAMUEL H. GIBSON.
